UNITED STATES PATENT OFFICE.

EDWIN J. BUSH, OF NEW YORK, N. Y.

BEADWORK-LOOM.

SPECIFICATION forming part of Letters Patent No. 737,073, dated August 25, 1903.

Application filed May 2, 1903. Serial No. 155,286. (No model.)

To all whom it may concern:

Be it known that I, EDWIN J. BUSH, a citizen of the United States, residing at the city of New York, in the county of New York and 5 State of New York, have invented certain new and useful Improvements in Beadwork-Looms, of which the following is a specification.

My invention has relation to a hand-loom 10 adapted for use in weaving beadwork; and in such connection it relates to the construction and arrangement of such a loom.

The principal object of my invention is to provide a loom of simple, inexpensive, and 15 strong construction wherein the warp-threads to which the beads are to be secured are properly supported in position, so as to be readily accessible, and in which the beaded work may be readily taken up during the 20 progress of the work.

The nature and scope of my invention will be more readily understood from the following description, taken in connection with the accompanying drawings, forming part hereof, 25 in which—

Figure 1 is a side elevational view, partly sectioned, of a loom embodying main features of my invention. Fig. 2 is a top or plan view thereof. Fig. 3 is a cross-sectional view illustrating one of the reeds in elevation, and Fig. 4 is a cross-sectional view illustrating the take-up mechanism for the work.

Referring to the drawings, *a* represents the base of the loom. At either end of the base 30 *a* are arranged bearings *b* and *d*, in which turn, respectively, the drums or rollers *b'* and *d'*. Immediately in front of each drum or roller *b'* or *d'* is arranged a reed *e* and *e'*, consisting, as shown, of a serrated bar *e²*, 35 supported upon uprights *e³*, projecting from the base *a*.

Parallel with the base *a* and clamped down thereon is a transverse bar *f*. The preferred clamping means for holding the bar *f* is an 40 elastic band *f*, engaging the ends of the bar *f* and extending beneath the base *a*, as illustrated in Fig. 4.

The base *a* is provided at one end with a series of holes or perforations *g*, into which 45 are fitted the pegs *g'*. Into these holes *g* are passed the warp-threads *m* prior to passing the same over the drum or roller *b'* and the

reed *e*. The pegs *g'* serve to clamp the threads *m* in the holes *g*.

The operation of the loom is as follows: 55 The warp-threads *m* in required number are drawn through one or more holes *g* and over the drum *b'*. The threads are then separated by entering the proper serrations of the bar *e²* of the reed *e* and the bar *e²* of the reed *e'*. 60 The threads *m* then pass over the drum *d'* and under the take-up bar *f* and are clamped by said bar to the base *a* of the loom, the band *f* furnishing the necessary clamping force for the bar *f*. After the threads *m* 65 have been properly assembled in the loom the beads *p* are united to these threads *m*, according to the pattern required, by passing the sewing or weft threads *p'* through the beads *p*, so as to unite the beads to the 70 threads. The manner of so uniting the beads is well known to those who make beadwork and needs no special description here. One way of uniting the beads to the warp-threads 75 *m* is illustrated in the drawings, and it consists in first threading a needle with a sufficient length of thread *p'*, then placing the beads *p* for one row of the pattern upon the needle. The needle, with the beads, is then passed under the warp-threads *m* and the 80 beads arranged between said warp-threads. The thread *p'* is then drawn through the beads *p* and under the warp-threads *m*, the end of the thread *p'* having first been tied to a warp-thread *m*, first in series. The thread 85 *p'* is then passed around a warp-thread *m*, last in series, and then through the beads *p*, passing over all the warp-threads in series. For the succeeding rows of beads *p* in the 90 pattern the same manipulation of the needle and thread *p'* is required—that is to say, each row of beads *p* is united to the warp-threads *m* by the weft-thread *p'*, which first passes under the warps and through the beads and then over the warps and through the 95 beads. After the work has progressed sufficiently the beaded portion is drawn over the drum *d'* and under the take-up bar *f*, the threads *m* having been first loosened in the hole or holes *g* by removing the peg or pegs 100 *g'*. After so taking up the work the warp-threads *m* are tightened by pulling them over the drum *b'* through the hole or holes *g*, and the peg or pegs *g'* are again used to bind the

threads to the base *a*. The warp-threads in the loom are thus held under proper tension in a position to be readily accessible, and the work may be properly and easily taken up 5 without disturbing the loom.

Having thus described the nature and object of my invention, what I claim as new, and desire to secure by Letters Patent, is—

1. In a loom of the character described, a 10 base, two drums supported above the base respectively at either end of said base, and two reeds interposed between the two drums, each reed consisting of a bar having a serrated edge supported above the base of the loom, 15 substantially as and for the purposes described.

2. In a loom of the character described, a base, two drums supported above the base respectively at either end of said base, two reeds 20 interposed between the two drums, each reed consisting of a serrated bar supported above the base of the loom, and one or more pegs arranged to enter suitable perforations in the base of the loom to confine the warp-threads 25 of the loom to said base.

3. In a loom of the character described, a base, two drums supported above the base respectively at either end of said base, two reeds interposed between the two drums, each reed consisting of a serrated bar supported above 30 the base of the loom adjacent to the drum, and a take-up for the work, comprising a transverse bar and an endless elastic band passed over the ends of the bar and under the base of the loom.

4. In a loom of the character described, a base having a drum supported above the same, reeds located between the respective ends of said loom and each consisting of a serrated bar, and pegs adapted to enter suitable 35 perforations in the base of said loom to confine the threads of the loom to said base.

In testimony whereof I have hereunto set my signature in the presence of two subscribing witnesses.

EDWIN J. BUSH.
